UNITED STATES PATENT OFFICE

115,410

DESIGN FOR A PLAQUE

Leonard C. Kotz and Arthur F. Kotz,
Syracuse, N. Y.

Application October 21, 1938, Serial No. 80,584

Term of patent 7 years

To all whom it may concern:

Be it known that we, Leonard C. Kotz and Arthur F. Kotz, citizens of the United States, residing at Syracuse, in the county of Onondago and State of New York, and having their post-office addresses at 909 Court Street, respectively, Syracuse, New York, have invented a new, original, and ornamental Design for a Plaque, of which the following is a specification, reference being had to the accompanying drawing, forming part thereof.

Figure 1 is a face view of a plaque showing our design.

Figure 2 is a longitudinal sectional view taken on line 2—2 of Figure 1.

The essential features of my design consist of the rectangular plaque shown in full lines in Figure 1, having a centrally located elliptical recess, a rim in relief bordering the recess, groups of ray-like projections extending from the rim of the central elliptical recess to the corners of the rectangular border, said ray-like projections being separated by fields of sky and clouds, the clouds being in relief.

We claim:

The ornamental design for a plaque, substantially as shown and described.

LEONARD C. KOTZ,
ARTHUR F. KOTZ.
